CLAIM

The ornamental design for a gas pizza oven, as shown and described.

DESCRIPTION

FIG. 1 is a top perspective view of a gas pizza oven design showing my new design.

FIG. 2 is a front view of a gas pizza oven.

FIG. 3 is a rear view of a gas pizza oven.

FIG. 4 is a left side view of a gas pizza oven.

FIG. 5 is a right side view of a gas pizza oven.

FIG. 6 is a top view of a gas pizza oven.

FIG. 7 is a bottom view of a gas pizza oven; and,

FIG. 8 is a bottom perspective view of a gas pizza oven. Any shading and cross-hatching are not features of the design but are utilized to illustrate the surface contours of the gas pizza oven design in the drawings.
